UNITED STATES PATENT OFFICE

151,942

DESIGN FOR AN ASTROLABE

Charles O. Rothweiler, Milwaukee, Wis.

Application March 4, 1947, Serial No. 137,348

Term of patent 14 years

(Cl. D57—1)

To all whom it may concern:

Be it known that I, Charles O. Rothweiler, a citizen of the United States, residing at Milwaukee, in the county of Milwaukee and State of Wisconsin, have invented a new, original, and ornamental Design for Astrolabes of which the following is a specification, reference being had to the accompanying drawings, forming a part thereof.

Fig. 1 is a side perspective view of an astrolabe, showing my new design.

Fig. 2 is a perspective view of the opposite side to that shown in Fig. 1; and

Fig. 3 is a top plan view of the same.

I claim:

The ornamental design for an astrolabe, as shown.

CHARLES O. ROTHWEILER.
